UNITED STATES PATENT OFFICE.

WINFIELD R. COE, OF WEST MERIDEN, CONNECTICUT, ASSIGNOR TO
CHARLES C. CLARKE, OF SAME PLACE.

HARNESS-SADDLE.

SPECIFICATION forming part of Letters Patent No. 236,553, dated January 11, 1881.

Application filed May 6, 1880. (Model.)

To all whom it may concern:

Be it known that I, WINFIELD R. COE, of West Meriden, in the county of New Haven and State of Connecticut, have invented a new 5 Improvement in Harness-Saddles; and I do hereby declare the following, when taken in connection with the accompanying drawings and the letters of reference marked thereon, to be a full, clear, and exact description of 10 the same, and which said drawings constitute part of this specification, and represent, in—

Figure 1, a side view; Fig. 2, a longitudinal central section; Fig. 3, a top view of the saddle-seat, saddle removed; Fig. 4, an under- 15 side view of the saddle; Fig. 5, a sectional front-end view with hook removed.

This invention relates to an improvement 20 in the construction of harness-saddles, the object being specially to secure the water-hook and avoid the use of nuts upon the under side 25 of the saddle-tree; and the invention consists in the construction as hereinafter described, and particularly recited in the claim.

The general outline of the saddle is not ma- 25 terially different from that of other constructions. A ring, *a*, extends down each side from the bridge *A*. At the front a hole, *b*, is bored to receive the shank *B* of the hook *C*, as seen in Figs. 2 and 5. The saddle *D* is constructed 30 with a projection, *d*, upon its under side, at the rear, which sets into a corresponding recess, *e*, in the saddle seat or bridge, and longitudinally through the projection *d* and through the saddle-seat a screw, *f*, is introduced, tapped

into the shank *B* of the hook *C*, as seen in 35 Fig. 2, which serves to bind the saddle to its seat, and also to secure the water-hook, avoiding the use of nuts, and making the hook more secure than where nuts are used.

To make the saddle *D* more secure, it is con- 40 structed at its forward end, upon the under side, with lugs *h*, of dovetail form, to set onto the corresponding dovetail-shaped projections *n* on the forward end of the saddle-seat. The back-strap loop *E* is secured by having its for- 45 ward portion set into a corresponding groove, *m*, in the saddle-seat, and so that the saddle *D* covers the groove and holds the loop in place, so that the single screw *f* serves to secure the hook *C* and loop *E*, and the saddle *D* 50 to its seat.

I do not claim any of the parts except in combination as hereinafter recited.

I claim—

The herein-described harness-saddle, con- 55 sisting of the saddle-tree *A*, the water-hook *C*, set in a recess, *b*, in the tree, the back-strap loop *E*, fitted into a groove in the tree, the part *D*, constructed with a projection, *d*, set in the recess *e* in the tree, and the screw *f*, through 60 the projection *d* in the pad, longitudinally through the tree, and into the shank of the hook *C*, to secure the several parts together, all substantially as described.

WINFIELD R. COE.
